(57) **CLAIM**

The ornamental design for a funnel with self supporting legs, as shown and described.

DESCRIPTION

FIG. 1 is a perspective view of a funnel with self supporting legs, showing the new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof; and,

FIG. 7 is a cross-sectional view thereof, taken generally along lines 7—7 of FIG. 5.
